US00D646015S

(12) **United States Design Patent**
Chiang et al.

(10) **Patent No.:** **US D646,015 S**
(45) **Date of Patent:** **** Sep. 27, 2011**

(54) **LIGHT EMITTING DIODE LAMP**

(75) Inventors: **Jen-Ta Chiang**, Taipei (TW); **Chia-Hao Liang**, Taipei (TW); **Hsin-Chang Tsai**, Taipei (TW)

(73) Assignee: **Everlight Electronics Co., Ltd.**, Taipei (TW)

(**) Term: **14 Years**

(21) Appl. No.: **29/362,093**

(22) Filed: **May 20, 2010**

(30) **Foreign Application Priority Data**

Nov. 20, 2009 (TW) 98305548

(51) LOC (9) Cl. **26-99**

(52) U.S. Cl. **D26/122**

(58) Field of Classification Search D26/72, D26/80, 120-122; 362/148, 240, 241, 247, 362/249, 330, 331, 545, 800

See application file for complete search history.

(57) **CLAIM**

The ornamental design for a lighting emitting diode lamp, as shown and described.

DESCRIPTION

FIG. 1 is a perspective view of an embodiment of a lighting emitting diode lamp showing our new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a cross-sectional view taken alone line **8-8**.

FIG. 9 is a cross-sectional view taken alone line **9-9**.

FIG. 10 is another perspective view thereof.

FIG. 11 is perspective view of another embodiment of the lighting emitting diode lamp showing our new design.

FIG. 12 is a front view thereof.

FIG. 13 is a rear view thereof.

FIG. 14 is a left side view thereof.

FIG. 15 is a right side view thereof.

FIG. 16 is a top view thereof.

FIG. 17 is a bottom view thereof.

FIG. 18 is a cross-sectional view taken alone line **18-18**; and,

FIG. 19 is a cross-sectional view taken alone line **19-19**.
